UNITED STATES PATENT OFFICE.

HENRY S. WEDMORE, OF GUILFORD, CONNECTICUT.

DESIGN FOR A BICYCLE-HOLDER.

SPECIFICATION forming part of Design No. 28,589, dated May 10, 1898.

Application filed March 23, 1898. Serial No. 674,942. Term of patent 7 years.

To all whom it may concern:

Be it known that I, HENRY S. WEDMORE, a citizen of the United States, and a resident of Guilford, in the county of New Haven and 5 State of Connecticut, have invented and produced a new and original Design for a Bicycle-Holder, of which the following is a specification, reference being had to the accompanying drawing, forming part thereof.

10 The leading feature of my design consists of a holder for bicycles, comprising a pair of skeleton cheeks having a general D shape, the standards of the D-shaped cheeks being extended between the loop portions at one end 15 of the holder.

In the accompanying drawing the standard

portions of the D-shaped cheeks are denoted by A A' and the loop portions by a a'.

Having described my invention, what I claim as new, and desire to secure by Letters 20 Patent, is—

The design for a bicycle-holder substantially as herein shown and described.

In testimony that I claim the foregoing as my invention I have signed my name, in presence of two witnesses, this 21st day of March, 1898.

HENRY S. WEDMORE.
